GARMENT SLEEVE IRONER

John H. Leef, Minneapolis, Minn., assignor to
Leef Bros., Inc., Minneapolis, Minn., a corpora-
tion of Minnesota

Application May 8, 1937, Serial No. 141,465

4 Claims. (Cl. 223—73)

My present invention relates to improvements in ironing machines of the type employed for ironing the tubular portions of garments such as legs and sleeves and, in the particular form 5 herein illustrated and described, is particularly adapted for the ironing of garment sleeves. Otherwise stated, the invention relates to improvements in ironing devices of the type disclosed in prior Patents Nos. 1,937,656 and 2,022, 10 210, the former of which was issued jointly to myself and George H. Leef on December 5, 1933 under the title of "Garment leg ironer," and the letter of which was issued jointly to myself and George H. Leef on November 26, 1935 under 15 the title of "Garment sleeve ironer."

Among the important objects of the invention is the provision of a machine of the kind described that can be more quickly and easily manipulated than similar machines of this character. The 20 above and several other important objects of the invention will be made apparent in the following specification and claims.

In the accompanying drawings like characters indicate like parts throughout the several views.

25 Referring to the drawings:

Fig. 1 is a transverse vertical sectional view with some parts shown in full and some parts broken away, taken on the line 1—1 of Fig. 2, looking from the right toward the left;

30 Fig. 2 is a vertical sectional view with some parts shown in full, taken on the line 2—2 of Fig. 1 and looking from the left toward the right in respect to Fig. 1;

Fig. 3 is a fragmentary sectional view similar 35 to Fig. 1 but being taken on the line 3—3 of Fig. 2 and looking from the left toward the right with respect to Fig. 2;

Fig. 4 is an enlarged detail view with some parts broken away and some parts shown in section; 40 and

Fig. 5 is a composite illustrating the inlet and outlet connections to the steam chambers of the several boots, and the series hook-up of the several thereof is indicated by direction arrows, the 45 several parts of this view being enclosed in broken lines.

Mounted on a common supporting table 6, which consists of a top 7 and a frame-like leg structure 8, are two pairs of co-operating pressing 50 boots, one of which pairs of boots is indicated as an entirety by A, and the other of which pairs of boots is indicated as an entirety by B. Each pair of boots is identical in character and is mounted in laterally spaced parallel relation on 55 the table top or supporting base 7. Each pair

of boots consists of a fixed or rigidly mounted boot 9 and a co-operating relatively movable boot 10. The boots 9 and 10 are in the nature of elongated hollow shells preferably cast of iron or other suitable metal of high conductivity. The 5 rigidly mounted or fixed boots 9 are securely anchored to the table top or supporting base 7 by suitable bolts or the like 11, and the co-operating relatively movable boots 10 are connected to and supported from their respective co-operating fixed boots 9 by links 12, which links are pivotally connected at their lower ends to the base portions of the fixed boots at 13 and to the upper intermediate portions of the movable boots 10 by pivot hinge pins 14. The co-operating boots 9 15 and 10 thus mounted, one with respect to the other, will automatically adapt themselves to relative positions necessary to accommodate different sizes and shapes of garment sleeves; and since it is desired to permit the boots 9 and 10 to be 20 brought into face-to-face contact when necessary, the opposed inner faces of the boots 9 and 10 are preferably provided with recesses 15 and 16 for reception of the connecting links 12.

Under the action of gravity the movable boots 25 10 will normally tend to move away from their respective co-operating boots 9 on the arc of a circle struck from the points of pivotal connection between the links 12 and fixed boots 9, and the tendency will be for the movable boots 10 to 30 move on this movable arc until the lower ends of the boots 10 come to rest upon the table top 7. However, in practice the resilient steam connections to the movable boots, which will hereinafter be described in detail, usually exert sufficient resistance to such extreme movement as is necessary to keep the movable boots normally positioned substantially as illustrated in Figs. 1, 2 and 3, wherein said boots 10 are positioned 35 slightly above the table top. Nevertheless, it will 40 be obvious that in the absence of sufficient resistance to gravitation set up by the steam connections the movable boots 10, when released, will normally come to rest against the top of the table. The boots 10 are concave from top to 45 bottom at their front faces, indicated by 17, and these concave portions 17 are spanned by resilient forming rods 18, the lower ends of which forming rods 18 are loosely seated in suitable sockets 19 formed in the base portions of the boots 10, and 50 the upper ends of the resilient forming rods 18 are turned inwardly at 20 and work slidably in grooves or notches 21 in the upper end portions of their respective boots 10. The inturned end portions of the forming rods 18 are retained 55

against upward movements out of the notches 21 by retaining pins or the like 22. By reference particularly to Fig. 4 it will be seen that the intermediate portions of the inturned upper ends 5 20 of the forming rods 18 are vertically offset at 23, and the notches 21 are similarly offset to provide stop shoulders 24 which co-operate with the opposite portions 23 of the forming rods to limit outward movements of the forming rods 18 10 with respect to the boots 10. Interposed over the extreme inner ends of the forming rods 18 and extending between the opposite portions 23 thereof and the rear wall of the notches 21 are compression springs 25 which normally keep the 15 ends of the pressing rods 18 pressed outward to the maximum extent permitted by the stop shoulders 24, but which springs 25 will yield readily under contracting pressure exerted by a garment sleeve and will permit the upper ends of the 20 forming rods 18 to be drawn up tight against the faces of their respective boots 10 or to any intermediate positions.

The sleeves of the shirts of various different grades and makes vary greatly in shape. Some, 25 namely, the lower quality work shirts, taper straight down from the shoulder to the cuff diameter at the cuffs; whereas, sleeves of higher quality shirts such as dress shirts, usually have much less taper and at their points of attachment to 30 the cuffs are of considerably larger diameter than the cuffs themselves. Still other shirts have sleeves which are substantially of uniform diameter throughout; and still other shirts are found to be provided with sleeves which are concave 35 adjacent the seam. It will be obvious that it would be practically impossible to select any shape pressing boots which would be capable of conforming to the shape of all the different sizes and styles of short sleeves encountered in general laundry practice, but such difficulty is largely 40 done away with in the preferred embodiment of this invention herein illustrated and described by the combined automatic shifting actions of movable boots 10 with respect to their co-operating boots 9 and the yielding action of the forming rods 18.

In this connection it will, of course, be understood that when a sleeve is pulled over a pair of co-operating boots 9 and 10, shoulder end first 50 and seam adjacent the forming rods 18, the movable boots 10, after being shifted toward their co-operating fixed boots 9 to permit free application of the sleeve, will move outwardly under the action of gravity until they tightly engage the 55 sleeve and maintain the same under expanding pressure against the surfaces of the boots, and the upper ends of the forming rods will compress their co-operating springs 25 and recede into the heads of the boots 10 as far as is necessary to accommodate sleeves of any particular cuff dimension; and the intermediate and lower portions 60 of the forming rods 18 will shape themselves to conform to the shape of the seam edge of any seam shape. The net result of the above is the 65 uniform stretching or shaping of substantially any sleeve shape all the way from cuff to shoulder without leaving any ruffled or loose portions, so that the finished product is substantially free from imperfections usually considered as a necessary 70 result of machine work.

Preferably the rear sides of the fixed boots 9, which engage the sleeve diametrically opposite the seam edge thereof, are straight or substantially so from top to bottom, but, of course, this 75 form may be varied. In the machine illustrated

the opposite pairs of pressing boots A and B are spaced so that both sleeves of a shirt may be pressed in a single operation.

Hitherto in machines of this character the boots have been drawn together to an extent necessary to accommodate a sleeve by the contracting action produced under first application of the sleeve. This practice, however, is objectionable, firstly, in that it retards the operation of inserting the sleeve, and secondly, in that it is apt to place undue and sometimes damaging strain upon the sleeve. It is therefore an object of this invention to provide a unique mechanism for forcing the boots together and into minimum diameter condition during the sleeve application and removal operations. In the preferred embodiment of the invention herein illustrated this retracting mechanism is foot-operated and comprises an intermediately pivoted operating lever 26 and a forked push rod 27, opposite upper ends 28 of which engage the bottom portions of opposite boots 10. These forked upper ends 28 of push rod 27 work freely through guide apertures 29 provided therefor in the table top 7, see particularly Fig. 1. The lower end of push rod 27 35 is pivotally anchored to the inwardly projecting end of the lever 26 at 30. The intermediate portion of the lever 26 is pivoted on a cross rod 31 that extends at opposite sides of the frame-like structure 8 and is held axially centered on said 40 rod 31 by opposed spacing tubes 32. Preferably the lever 26 is provided at its outer end with a pedal plate 33 which is conveniently positioned for manipulation by one of the operators.

Under foot pressure applied by the operator to 35 to the pedal-equipped end of the lever 26, lifting pressure will be applied to the movable boots 10 through the forked push rod 27, and under this upward lifting pressure the movable boots 10 will tend to move upwardly and toward their 40 respective co-operating fixed boots 9 on the arcs of circles struck from the pivot points 13 until the upper ends of the co-operating boots come into engagement, at which time application of the sleeve will be very quickly accomplished. 45 After the sleeve has been applied and the foot pressure released, the parts will then assume positions necessary for complete smoothing out of all the sleeve surface. Since the upper ends 50 of the push rod engage the base portions of the movable boots 10 only with frictional surface engagement, movements of the lower ends of the boots 10 will be permitted even when lifting pressure is applied to the boots and lever 26 of the push rod.

The steam chambers within the hollow shell-like boots 9 and 10 of boot pairs A and B are supplied with suitable heating medium, which will usually be live steam in the manner presently to be described. These steam chambers 60 of the several boots are each provided with concentric steam inlet and outlet ducts, and the steam chambers of the several boots are connected in series. For this purpose each of the several boots 9 and 10 has projecting downwardly 65 from the screw threaded into its bottom portion a pipe-like section. For the purpose of identification the said outlet pipe sections for boots 9 and 10 of boot pair A are respectively indicated by 9a and 10a and said pipe outlet sections for boots 9 and 10 of boot pair B are respectively indicated by 9b and 10b. Each of the several outlet pipe sections 9a, 10a, 9b and 10b is provided at its lower end with a conventional T-coupling 70 34. The outlet pipe sections 10a and 10b of the 75

movable boots 10 work through slots 35 provided in the table top 7, so that the said pipe sections will not interfere with free oscillatory movements of the movable boots.

5 Steam is introduced through the serially connected series of boots through a primary inlet pipe 36 which is screw threaded into the lower vertical opening of the T-coupling 34 that is carried by the outlet or discharge pipe 9a of fixed boot 9 of pair A. Projecting concentrically from the upper end of the primary inlet conduit 36 and through the associated coupling 34 and outlet duct 9a and into the upper portion of the steam chamber of boot 9 of pair A is a relatively 10 small diameter conduit 37 in the nature of a drawn copper tubing. This conduit 37 is secured in the end of the conduit 36 by a conventional compression type fitting 38 which tightly seals the space between the small diameter conduit 37 and the larger internal diameter of the primary inlet pipe 36. Steam delivered through the primary inlet pipe 36 passes upwardly through the small diameter conduit 37 to the upper extremity of boot 9 of pair A and then passes downwardly 15 through the steam chamber of said boot around the outside of said conduit 37 and discharges from the boot 9 of pair A through outlet conduit 9a into the intermediate portion of the associated T-coupling 34. The horizontal opening of this last noted T-coupling 34 is connected through the medium of a compression type fitting 39 to a small diameter conduit 40, which extends through the bottom of coupling 34 of conduit 10a through the center of conduit 10a and to the upper extremity of the steam chamber of boot pair A. This pipe coupling 40 is secured in the coupling 34 of conduit 10a by a compression type fitting 41. By means of this connection steam discharged from the boot 9 of pair A is 20 delivered to the boot 10 of pair A, and steam discharged from boot 10 of pair A through coupling 10a is delivered to the upper extremity of boot 10 of pair B by a small diameter tubing or conduit 42, which tubing is made fast in T-coupling 34 in conduit 10a by a compression fitting 43 and is made fast in the T-coupling 34 of conduit 10b by a compression fitting 44. Steam delivered into the boot 10b through the conduit 42 will be discharged through the conduit 10b into the associated coupling 34, from where it 25 will be delivered through a small conduit 45 to the upper extreme portion of the steam chamber of boot 9 of pair B. Conduit 45 is made fast in the associated couplings 34 by compression fittings 46 and 47. Steam thus delivered into the 30 steam chamber of boot 9 of pair B will be discharged through pipe 9b into the associated coupling 34 and from thence will be discharged through a suitable final outlet pipe 48.

As previously indicated, the conduits 40, 42 and 45 are preferably of drawn copper tubing which is quite flexible, and in order to increase to a maximum the flexing action of the portions of these conduits which connect to either of the 35 movable boots 10, these portions of the conduits 40, 42 and 45 are coiled, as indicated in Figs. 1, 2 and 3. Interposed in the final outlet pipe 48 is a steam-control valve 49.

In the preferred embodiment of the invention illustrated the table top 7 is provided with a 40 pair of stop lugs 50, one thereof being located back of the base portion of each of the boots 10 and so positioned as to be engaged by the lower portions of the boots 10 under maximum

desired outward oscillating movements thereof and to prevent excessive outward oscillation of the lower portions of said boots.

With the structure above described, it is evident that while the movable boots will be simultaneously lifted and caused to approach the co-operating fixed boots, under the action of the lifting device afforded by the push rod 27-28, nevertheless, that the independent supporting links 12 and the loose or slip connection between the rod prongs 28 and the bottoms of the movable boots 10 permit the latter, when manually pressed by the application of a garment leg, sleeve, or the like, to approach the co-operating fixed boots and thus adapt themselves to legs 15 or sleeve structures that differ in cross-section and taper.

What I claim is:

1. In a device of the kind described, the combination with a table-like supporting structure, 20 of a pair of co-operating upright pressing boots, one of which boots is relatively fixed to said supporting structure and the other of which boots is movable toward and from the fixed boot, a link connected at its lower end to the base portion of 25 said fixed boot and at its upper end to an upper portion of said movable boot and supporting the latter for rocking movements and for movements toward and from said fixed boot, and a lifting device movable vertically through said supporting structure and having sliding or slipping engagement with the lower end of said movable boot.

2. In a device of the kind described, the combination with a table-like supporting structure, 35 of two pairs of co-operating upright pressing boots, each pair including one boot fixed to said supporting structure and one boot movable toward and from the fixed boot, independently movable links connected at their lower ends to 40 the base portions of the fixed boots and at their upper ends to upper portions of the co-operating movable boots and supporting the latter for independent rocking movements and for independent bodily movements toward and from the co-operating fixed boots, and a lifting device movable vertically through said supporting structure and having independent sliding or slipping engagement with the lower ends of the respective movable boots.

3. In a device of the kind described, the combination with a table-like supporting structure, 50 of two pairs of co-operating upright presser boots, each pair including one boot fixed to said supporting structure and one boot movable toward and from the fixed boot, independently movable connections supporting said movable boots for independent rocking movements and for independent bodily movements toward and from the co-operating fixed boots, and a common lifting device mounted on said supporting structure and having simultaneous lifting movements on said movable boots but permitting said movable boots to be independently moved toward the co-operating fixed boots under force applied 55 thereto by means other than said common lifting device.

4. The structure defined in claim 2 in which said independent supporting links are so disposed that the movable boots will tend to move 60 away from the co-operating fixed boots under the action of gravity.

JOHN H. LEEF.
